DIGITAL CLOCK-LAMP

Jack Bergman, Pittsburgh, Pa., assignor to Pennwood
Numechron Co., Pittsburgh, Pa.

Filed July 29, 1971, Ser. No. 167,547

Term of patent 14 years

Int. Cl. D10—01

U.S. Cl. D42—7

FIG. 1

FIG. 2

FIG. 3

FIG. 1 is a top plan view of a digital clock-lamp showing my new design;

FIG. 2 is a front elevational view thereof;

FIG. 3 is a right side elevational view, the left side being a mirror image thereof.

I claim:

The ornamental design for a digital clock-lamp, as shown and described.
